UNITED STATES PATENT OFFICE.

FREDRIC M. PARKER, OF WORCESTER, MASSACHUSETTS, ASSIGNOR TO
WILLIAM JAMES HOGG & SON, OF SAME PLACE.

DESIGN FOR CARPET.

SPECIFICATION forming part of Design No. 26,961, dated April 20, 1897.

Application filed March 1, 1897. Serial No. 625,672. Term of patent 3½ years.

To all whom it may concern:

Be it known that I, FREDRIC M. PARKER, a citizen of the United States, residing at Worcester, in the county of Worcester and State of Massachusetts, have invented and produced a new and original Design for Carpets, of which the following is a specification.

My invention relates to a design to be worked into or upon carpeting or similar fabrics, and I do hereby declare that the drawing accompanying this specification gives and conveys to any one skilled in the art of carpet-weaving a clear understanding of the same that is sufficient to enable such person to use my invention.

The said drawing is a face view of a carpet embodying my new design.

The drawing illustrates a body and a border.

The body A consists of a substantially uniform groundwork upon which appear small figures of an elongated - lozenge shape arranged diagonally as to each other. A dot is placed in each space between the figures.

The border B is divided into narrow upright panels formed by branching stems and

containing figures similar to those in the body. The outer edge is characterized by conventional floral figures, each of a substantial cup shape, with an arch of small conventional flowers springing from it. These are alternated diagonally by figures formed by curving leafwork springing from a small floral base and forming a substantially conventional bud shape.

The colors employed for the different portions of this design may be varied to suit the convenience or taste of the manufacturer.

What I claim, and desire to secure by Letters Patent, is—

1. In a design for carpeting, the body A, substantially as shown.
2. In a design for carpeting, the border B, substantially as shown.
3. The design for carpets, consisting of the body A and the border B, substantially as shown.

FREDRIC M. PARKER.
